UNITED STATES PATENT OFFICE.

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS.

GRINDING WHEEL.

Original application filed March 16, 1923, Serial No. 625,469. Divided and this application filed January 9, 1925. Serial No. 1,336.

In application Serial No. 625,469 filed March 16, 1923, I have disclosed a machine for grinding gear wheels, sprocket wheels and similar toothed bodies of revolution. 5 This machine includes a novel grinding wheel adapted to generate the finished tooth surfaces as the gear wheels are rolled across its periphery. The present application is a division of said application Serial No. 10 625,469.

In the accompanying drawings, Figure 1 is a fragmental plan view of a grinding machine embodying the features of my invention.

15 Fig. 2 is a fragmental view illustrating the operation of grinding one side of each tooth of a blank.

Fig. 3 is a fragmental view representing the operation of grinding the other side of 20 the tooth of a blank.

For the sake of brevity, the gear wheels, the sprocket wheels or other articles to be ground will be hereinafter referred to as "blanks".

25 The grinding wheel A constituting the subject of this invention has on its periphery a series of equidistant annular ribs A'. For the sake of accuracy in grinding and simplicity in dressing, the grinding wheel is 30 so constructed that only flat surfaces are utilized for grinding the teeth of the blanks.

To this end the grinding wheel is given a frusto-conical form, one side of each of the ribs A' being perpendicular to the axis of 35 the grinding wheel. The grinding surfaces are indicated by the letter a. In a single passage of a blank across the periphery of the grinding wheel, only one side of each tooth is ground. In order that the opposite 40 side of each tooth may be ground the blank is positioned so as to present such opposite side of the tooth to the abrasive wheel, whereby the grinding of both sides of each tooth is effected in two passages of the blank 45 across the grinding wheel. It will be evident from Figs. 2 and 3 that during one passage of the blank the flat surfaces a constituted one side of each tooth of an imaginary rack and that during the other passage 50 of the blank said surfaces constitute the opposite side of said rack teeth.

The blanks are indicated at b. Each blank is rigidly secured to an arbor c by means of which the blank is supported dur-

ing the grinding operation and during its 55 travel in the machine, and through which rolling movement is imparted to the blank while it is passing the grinding wheel. The grinding wheel has the same number of grinding surfaces a as there are teeth on the 60 blank, consequently it is possible to pass three blanks in close succession past the wheel. I therefore support the blanks on cars 4, each adapted to support three arbors c. Suitable means, such as master gearing, 65 may be provided to cause the blanks to roll across the periphery of the grinding wheel in the travel of the car.

It will be seen that while a blank b is being rolled past the periphery of the grinding wheel on one side of the latter, one side 70 of each tooth of the blank will be ground, and that while the blank is rolling past the grinding wheel diametrically opposite the place where the first grinding operation occurs, the other side of each tooth will be 75 ground.

The grinding wheel is made of sufficiently large diameter so that the necessary peripheral speed is obtained at the small end of 80 the wheel. The diameter of the grinding wheel may be so great with relation to the thickness of the blank that there is no objectionable concaving of the bottoms of the interdental spaces of the blank. 85

I claim as my invention:

1. A frusto-conical gear grinding wheel having upon its periphery a plurality of equidistant annular plane grinding surfaces which are perpendicular to the axis of the 90 wheel.

2. A gear-grinding wheel having on its periphery a series of plane grinding surfaces constituting in effect elements of a series of imaginary rack teeth, said wheel 95 being of relatively large diameter and wide peripheral face as compared with the diameter and thickness of the gear to be ground.

3. The combination of a plurality of rotary equidistant annular plane gear grinding surfaces, each perpendicular to its axis of rotation, the number of said surfaces being equal to the number of teeth on the blank to be ground. 10

In testimony whereof, I have hereunto 105 affixed my signature.

HOWARD D. COLMAN.
